UNITED STATES PATENT OFFICE.

GEORGE A. SCHWAB, OF WASHINGTON, DISTRICT OF COLUMBIA.

BUTTON.

1,355,623.

Specification of Letters Patent. Patented Oct. 12, 1920.

Application filed April 19, 1920. Serial No. 374,961.

To all whom it may concern:

Be it known that I, GEORGE A. SCHWAB, a citizen of the United States, residing at the city of Washington, in the District of Columbia, have invented new and useful Improvements in Buttons, of which the following is a specification.

This invention relates to buttons, and it comprises a body portion, a spaced plate secured to the body portion, said plate having an aperture therein, and securing means consisting of a resilient strip of metal adapted to be received in said aperture, said resilient strip being removable and being provided with thread receiving openings for attaching the button to a garment, or other article, all as more fully hereinafter set forth and as claimed.

Buttons are generally secured to garments by sewing. When cloth covered buttons are used for ladies' garments, the threads are sewed directly to the cloth, at the back of the button. If thread is used sufficiently strong to hold the button, the cloth, which is generally of delicate texture to match the garments wears out, and the button comes off. Frequently it is lost, and generally it is unfit for further use because there is nothing to attach the threads to.

In this invention, I have produced a construction wherein the threads are secured to a member of resilient metal. The body portion of the button is separable or removable from this resilient member, and may be secured thereto after the member has been sewed to the garment. This permits the use of different sets of buttons with a single garment, and permits interchange of buttons without the necessity of sewing them to the garment each time. A lost button may be replaced by inserting the resilient member sewed to the garment, in the button.

In upholstery, buttons are sewed to the articles of furniture. In applying them it is difficult to sew the buttons on a finished article as the back of the button, where the threads are to be secured, is inaccessible. By the use of the present construction, the resilient members may be easily sewed to the article being upholstered, and the buttons readily applied.

In the drawings I have shown an advan-

tageous embodiment of this invention. In this showing,

Figure 1 is a plan view of the back of the button;

Fig. 2 is a section in the plane 2—2, Fig. 1; and

Fig. 3 is a detail view of the resilient member.

Referring to the drawings, the reference numeral 1 designates a strip of rigid material forming the back of the button. A shell 2 is secured to this strip, and the entire body portion may be provided with a covering of cloth or other suitable material 3. A plate of suitable material 4 is secured to the back of the button, and is slightly spaced from the strip 1. This plate is provided with a central aperture 5.

The means for securing the button to a garment or other article, consists of a resilient member 6. This resilient member comprises a central portion 7, and offset ends 8. The ends 8 are adapted to enter the aperture 5, and are positioned between the strip 1 and the spaced plate 4. The offset arrangement of the ends disposes the central portion 7 a slight distance from the back of the button, which is advantageous in placing the button on the securing strip. The resilient member is best sewed to the article to which the button is to be attached, and it may be provided with thread openings 9 for the reception of the thread.

The construction and operation of this button will be readily apparent. The resilient member is first sewed to the garment or other article, and then compressed to the dotted line position as shown in Fig. 2, of the drawings. The button is then placed over it, with the ends 8 of the resilient member in the aperture 5, and the resilient member released. The ends 8, then enter the space between the spacing plate 4 and the body portion of the button, securing the button to the article.

One of the disadvantages of using buttons sewed to garments, is that the button frequently becomes caught in doors, when the wearer of the garment is passing through and results in tearing the fabric. Where the present construction is employed the resilient member will give before the fabric can tear, and permit the button to fall off.

The button can then be easily replaced and tearing of the garment is prevented.

What I claim is:—

1. A button comprising a body portion, 5 a spaced plate secured to the back of the body portion, said plate having an aperture therein, and a resilient member adapted to be sewed to the article to which the button is attached, the ends of said resilient member being adapted to enter said aperture in the spaced strip and be received between said strip and the body portion of the button.
2. A button comprising a body portion, 10 a spaced plate secured to the back of the body portion, said plate having an aperture therein, a resilient member, having a central portion and offset ends, the offset ends being adapted to be received in said aperture when the resilient member is compressed, and to
- 15

enter the space between the body portion 20 and the spaced plate to secure said resilient member to the button.

3. A button comprising a body portion, a spaced plate secured to the back of the body portion, said plate having an aperture therein, a resilient member, having a central portion and offset ends, the offset ends being adapted to be received in said aperture when the resilient member is compressed, and to enter the space between the body portion 25 and the spaced plate to secure said resilient member to the button, said resilient member being provided with apertures to allow threads to pass therethrough to attach resilient member to a garment.

In testimony whereof, I affix my signature.

GEORGE A. SCHWAB.
